UNITED STATES PATENT OFFICE.

THOMAS CORSCADEN, OF NEW BRITAIN, CONNECTICUT, ASSIGNOR TO THE STANLEY WORKS, OF SAME PLACE.

DESIGN FOR A SHELF-BRACKET.

SPECIFICATION forming part of Design No. 25,785, dated July 14, 1896.

Application filed December 15, 1894. Serial No. 531,976. Term of patent 14 years.

To all whom it may concern.

Be it known that I, THOMAS CORSCADEN, a citizen of the United States, residing at New Britain, in the county of Hartford and State of Connecticut, have invented and produced a new and original Design for a Shelf-Bracket, of which the following is a specification, reference being had to the accompanying drawings, forming part thereof, in which—

10 Figure 1 is a perspective view of a shelf-bracket showing my design, and Fig. 2 is a side elevation of the same.

A designates the wall-plate, and B the shelf-plate, each of which terminates in a rounded end 3, having a circular bead 4 around the hole 5. A like bead, but smaller, as at 6, surrounds the outer screw-holes 7. The body of each wall and shelf plate is of a strap-like form with straight and parallel edges.

Upon the front of the wall-plate and under 20 side of the shelf-plate is a projecting rib 8, which extends to a point near the circular beads 4, its ends being formed on a double or ogee curve. At the junction of the two ribs 8 8 there is a raised portion 9 on each broad 25 side, as shown on one side in Fig. 2. A curved brace C extends from the rib 8 of one plate to the rib 8 of the other plate, as shown, and immediately opposite the ends of said brace the ribs have a semicircular raised portion 9, as shown.

What I claim is—

The design for a shelf-bracket substantially as herein shown and described.

THOMAS CORSCADEN.
